P. S. KNITTEL,
CRUSHER AND PULVERIZER,
APPLICATION FILED JAN. 2, 1918.

1,282,239.

Patented Oct. 22, 1918.

UNITED STATES PATENT OFFICE.

PAUL S. KNITTEL, OF ST. LOUIS, MISSOURI, ASSIGNOR TO AMERICAN PULVERIZER COMPANY, OF ST. LOUIS, MISSOURI, A CORPORATION OF MISSOURI.

CRUSHER AND PULVERIZER.

1,232,828.

Specification of Letters Patent. Patented Oct. 22, 1912.

Application filed January 2, 1912. Serial No. 216,092.

To all whom it may concern:

Be it known that I, PAUL S. KNITTEL, residing in the city of St. Louis and State of Missouri, have invented a certain new and 5 useful improvement in Crushers and Pulverizers, of which the following is a specification.

This invention relates to machines for crushing and pulverizing rock, coal, shale, 10 clay, and other material, and more particularly to a machine of the centrifugal type and comprising a casing or inclosing shell having circumferentially arranged breaking, crushing, grinding or sifting surfaces therein, and 15 a revolatory cage or carrier having circumferentially disposed pivotal hammers or rings mounted loosely thereon so as to stand out radially in co-operative relation to said surfaces when said cage or carrier is rotated at 20 a relatively high speed.

The invention has more particularly to do with the adjustment of the hammers or rings to bring them closer to, or farther away from, the opposed working surfaces of 25 the casing above mentioned, as the case may be, so as to compensate for wear and to vary the degree to which the material is reduced.

The invention consists in the parts and in the combinations and arrangements of 30 parts hereinafter described and claimed.

In the accompanying drawing which illustrates a practical embodiment of the invention, —

Figure 1 is a side elevation of a machine 35 mounted as ready for use, a portion of the casing being broken away to disclose the interior arrangement;

Fig. 2 is a fragmentary section taken approximately on the line 2—2 of Fig. 1; and 40 Fig. 3 is a fragmentary section taken approximately on the line 3—3 of Fig. 2.

The machine as illustrated in the drawing 45 comprises a circular casing in whose opposite side walls 1 and 2 are bearings 3 for the power shaft 4 which extends horizontally through the casing and, in practice, is provided in its end portions, outside of the casing, with the usual fly-wheel and driving pulley (not shown). At the front of the 50 machine is the usual feeding hopper 5 whose end wall 6 constitutes, or is provided with, an inclined tangential breaker-plate or crushing surface with which the centrifugal element, to be presently described, co-operates. The angular wall of the casing is provided with the usual grinding, reducing or

sifting surfaces on which the material is acted upon by the centrifugal element after leaving the initial breaking or crushing surface of the wall 6.

As shown, the centrifugal element comprises circular disks 7 which are keyed or otherwise securely fastened on the power shaft 4 close to the inner faces of the side walls 1 and 2 of the casing, the side walls 65 having suitable recessed portions 8 to receive said disks so as to have the inner faces of the side walls and disks flush with each other or nearly so.

Suitable spiders 9 are secured on the power shaft 4 between the disks 7, and in such number as is necessary according to the size of the machine or number of hammer elements or rings 10 to be used. As shown, there is but one spider, as there are only two series of such elements 10 in the machine (see Fig. 2).

The hammer elements or rings 10 are mounted loosely on eccentric shafts whose end portions 11 are fitted rotatably in suitable apertured portions 12 of the disks 7 near the peripheries thereof, and there normally held against rotation by set-screws 13 or other suitable fastening means. These shafts are also arranged for rotatable engagement with the spider arms, as at 14, said portions 14 being obviously concentric with the end portions 11. Between the end portions 11 and the intermediate spider-engaging portions 14 are the eccentric hammer-supporting or ring-supporting portions 15, as best shown in Figs. 2 and 3.

Obviously, by turning the eccentric shaft in its bearings in the disks 7 and spider 9, the hammers or rings 10 are supported closer to, or farther away from, the axis of the power shaft, as the case may be, and, consequently, the hammer or rings are accordingly made to travel closer to, or farther away from, the respective working surfaces 100 of the casing with which they co-operate.

While the construction and arrangement of the eccentric shaft, and the means for fastening it in adjusted position, as shown, is in its most simple and practical form, it is obvious that it admits of considerable modification and changes without in the least departing from the spirit of the invention as defined by the appended claims.

What is claimed is:

1. In a pulverizing machine, the combination with a power shaft, a carrier mounted

thereon, a supporting shaft mounted in said carrier, beaters mounted on said supporting shaft, said supporting shaft having concentric circular portions rotatably mounted in the carrier with integral eccentric portions between its concentric circular portions on which the beaters are mounted, and means for securing said shaft in every rotative adjustment thereof.

10 2. In a machine of the character described, a centrifugal reducing element comprising a power shaft, carrier members fastened on said power shaft in parallel and spaced relation to each other, said carrier members having aligned plain circular apertures whose

axes are parallel with the axis of said power shaft, a supporting shaft having corresponding portions fitted rotatably in the apertures of said carrier members with eccentric portions between its end portions, circumferentially disposed beaters mounted loosely on said eccentric portions of said supporting shaft, and releasable means for securing said supporting shaft in any position of rotative adjustment on said carrier members.

Signed at St. Louis, Missouri, this 31st day of December, 1917.

PAUL S. KNITTEL.
